(57) CLAIM

The ornamental design for a display screen or portion thereof with icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with icon showing a first embodiment of claimed design; FIG. 2 is a front view of a display screen or portion thereof with icon showing a second embodiment of claimed design; FIG. 3 is a front view of a display screen or portion thereof with icon showing a third embodiment of claimed design; FIG. 4 is a front view of a display screen or portion thereof with icon showing a fourth embodiment of claimed design; and,

FIG. 5 is a front view of a display screen or portion thereof with icon showing a fifth embodiment of claimed design. The broken lines shown in FIGS. 1-5 depict portions of a display screen and form no part of the claimed design.

1 Claim, 5 Drawing Sheets
(5 of 5 Drawing Sheet(s) Filed in Color)
